CAN DOUBLE SEAMING MACHINE

Henry L. Guenther, Los Angeles, Calif.

Application April 23, 1938, Serial No. 203,875

1 Claim. (Cl. 113—14)

This invention relates to can machinery, and particularly pertains to a can double seaming machine.

In the operation of machines for applying a cap to the body of a can of the type known as a sanitary can and to which the cap is attached by a double seaming operation it is desirable to perform the operation rapidly and in a workman-like manner. When the cans are filled with liquid or semi-liquid materials before the caps are applied and particularly when these cans are of relative large size, such for example as when having a gallon capacity, there is a tendency for the material to be disturbed within the cans and to be spilled therefrom as the cans move through the machine. It is the principal object of the present invention, therefore, to provide a can double seaming machine which will conduct a filled can through the machine at a relative rapid rate of speed, and with a minimum amount of disturbance which would cause the contents of the can to be spilled. The structure embodies means for delivering caps to the can body as the can advances to the double seaming station, and further embodies novel means whereby the can and cap are moved to an assembled relationship to the double seaming station and are thereafter joined together by a double seaming operation.

The present invention contemplates the provision of a can double seaming machine having a double seaming station to which cans are delivered by an intermittent feed device which moves the cans along a linear path of travel to and from the double seaming structure. The machine being further fitted with means to provide a can cap for a can as it reaches the double seaming station and without interruption of the can in its movement thereto, after which the can is "rounded" and the cap assembled therewith.

The invention is illustrated by way of example, in the accompanying drawings in which:

Figure 1 is a view in side elevation showing the machine with which the present invention is concerned;

Figure 2 is a view in plan showing the machine as previously disclosed in Figure 1;

Figure 3 is a view in horizontal section showing the machine as viewed on the line 3—3 of Figure 1, and indicating particularly the path of travel of the cans through the machine and showing a can disposed between two star wheels at the double seaming station;

Figure 4 is an enlarged view in central vertical section through the machine as seen on the line 4—4 of Figure 1, and viewed in the direction of 55

the arrows and showing a can receiving spider at the double seaming station;

Figure 5 is a view in horizontal section through the machine as seen on the line 5—5 of Figure 4 and discloses part of the driving mechanism;

Figure 6 is a view in horizontal section through the machine as seen on the line 6—6 of Figure 4, and discloses the intermittent driving mechanism of the machine;

Figure 7 is an enlarged view in section and elevation showing the lateral adjustment for the star wheel spindle;

Figure 8 is a view in transverse section as seen on the line 8—8 of Figure 7.

15 Referring particularly to the drawings, 10 indicates a base of the machine with which the present invention is concerned. This base as disclosed in Figure 4 is hollow and provides an enclosure for mechanical driving elements to be hereinafter described. The top of this base is indicated at 11 and forms a direct support for the super-structure of the machine. Upright elements 12 are connected to the base and provide guideways for an upper frame structure 13. 20 Bolting plates 14 are connected to these guideways by cap screws 15 which hold the plates in position and confine guide plates 16 for vertical movement. The guide plates 16 are a part of the upper frame 13. The upright elements 12 are formed as a part of a standard 17 which is secured to the top face 11 of the base 10 by cap screws 18. The standard is hollow and is formed with a vertical boss 19, in its upper end. A nut 20 fits into this boss and is held by cap screws 25 21. The interior of this nut is threaded to receive a vertically extending screw shaft 22 which extends upwardly and has an upper end portion 23 of reduced diameter. The portion of reduced diameter fits within a boss 24 formed in a horizontal element 25 of the upper frame structure 13. A nut 26 is threaded on to the upper end of the portion 23 and rigidly holds the shaft screw 22 in assembled relation with the upper frame structure. Pinned on to the shaft 22 at a point 30 45 directly beneath the boss 24 is a hand wheel 27 which when rotated will rotate the shaft 22 and produce vertical adjustment of the upper frame structure 13 with relation to the base 10. Due to this arrangement it is possible to quickly adjust the machine for operation upon cans of different height. Extending vertically through the boss 28, shown as formed integral with the base, is a composite main drive shaft 29. This shaft is here shown as being in three sections. A lower section 30, an intermediate tubular section 31 and an up-

per section 32. The tubular section 31 telescopes over the shaft 29 and is fastened with relation thereto by key 33 and pin 33'. The upper end of the tubular section is formed with a longitudinally extending keyway 34 to receive a spline 35. The spline is carried upon the upper shaft section 32 so that the members 31 and 32 will have longitudinal telescopic movement with relation to each other without interrupting the driving action of the entire shaft. This relative movement accommodates the adjustment of the base to the upper frame structure as effected by rotation of the screw shaft 22. A bearing 36 is formed vertically through the horizontal portion 25 of the upper frame structure 13 and rotatably supports the upper end of the shaft section 32. Mounted upon the upper end of this shaft is a drum cam 37 provided for a purpose to be hereinafter described and a bevel gear 38'. The horizontal portion 25 of the upper frame carries opposite horizontally aligned bearings 39. These are spaced from each other and receive a jack shaft 40. The jack shaft 40 is driven through a pulley 42 and a clutch element 43. Parallel to shaft 40 is a shaft 41. This shaft carries a bevel pinion 44 which is in mesh with the bevel gear 38' and by which the main drive shaft 29 is driven. Mounted upon this shaft is a gear 45, in mesh with pinion 46 on shaft 40. A suitable cover 47 is mounted over the jack shaft 41 and cooperates with the frame structure 13 to provide an enclosed housing for the upper gear mechanism.

A bevel gear 48 is in mesh with a bevel pinion 48' which is carried upon a vertical shaft 49. The shaft 49 extends through a bearing 50 adjacent to its upper end, and which bearing is a part of the horizontal frame portion 25. The lower end of this shaft extends through a bottom cover 51 which is secured in position by screws 52. This bottom cover carries a bearing 53. It will thus be seen that a completely closed compartment 54 is formed around the shaft when the cover plate 51 is in position. Mounted upon the shaft 49 is a gear structure comprising an upper gear 55 and a lower gear 56. These gears are in mesh with pinions 57 and 58. The pinions rotate around a common axis established by a chuck spindle 59 which is supported in an upper bearing 60 formed as a part of the horizontal frame portion 25, and a lower bearing 61 detachably secured to the cover plate 51. This lower bearing carries anti-friction bearings 62. The lower end of the chuck spindle 59 is provided with a chuck 63 which fits within the recess cavity in the top of can caps 64 as they are held in seaming relation with can bodies 65. Mounted upon the chuck spindle 59 and freely rotatable with relation thereto is an inner sleeve 66 and outer sleeve 67. The inner sleeve carries the gear pinion 57. The outer sleeve carries the gear pinion 58. Mounted at the lower end of the sleeve 66 is a spider 68 which circumscribes the sleeve and carries lugs 69. These lugs are provided with pivot pins 70 and upon them operating levers 71 are mounted. There are preferable four of these levers arranged in pairs upon diametrically opposite sides of the axis of the spindle 59. These levers carry double seaming rollers 72.

One pair of diametrically disposed rollers is provided to perform the first double seaming operation, and the other pair is provided to perform a second seaming operation as described in my issued Patent No. 2,052,620 entitled Double seaming machine and issued to me on the 1st day of September, 1936. The upper ends of the levers

71 carry rollers 73. One set of rollers engages a circular cam 74 and the other set of rollers engages a circular cam 75. The circular cams are integral and are fixed upon the sleeve 67 by 5 which they are rotated independent of the rotation of the spider 68. Mounted in the base and vertically reciprocating with relation thereto is a lower chuck spindle 76. This spindle is slidably mounted in vertically aligned bearings 77 and 78. 10 At its upper end it carries a nonrotatable chuck 79 which has a central split cavity 80 extending across and through it to accommodate a can conveyor chain 81. Suitable chuck plates 80' are mounted upon the chuck 79 at opposite sides of 15 the space 80 and are shaped to fit within the recessed bottom cap carried by the can body 65. The chuck 79 and its hub are housed within a cylindrical housing element 82 which is fixed upon the top 11 of the base 10. This housing element is substantially spool shaped having an upper flange 83 and a lower flange 84. A bearing opening is formed through these flanges to receive shaft 85. The shaft 85 carries a star wheel 87. 20 25 The shaft 85 is fitted at its lower end within a bearing bracket 88 which is spaced from a bearing 89. Disposed between the bearings 88 and 89 is a driving gear 90 which is splined on to the shaft 85 and will maintain driving relation between the gear and the shaft while permitting longitudinal adjustment of the shaft 85. This adjustment is provided by a sleeve 91 which carries a set screw 92 engaging the shaft 85. The gear 90 is driven through suitable means which 30 will be hereinafter described. Mounted upon the spindle 76 is a bearing plate 94 which is pinned to the spindle 76. Slidably mounted upon the lower end of the spindle is a pressure plate 95. This plate is spaced from the plate 94 by a plurality of rubber blocks 96 which are mounted upon bolts 97 and provide a cushion between the members 94 and 95. The pressure plate 95 is fitted with opposite side trunnions 98 which are engaged by the arm 99 of a rocking lever 100. The rocking lever 100 is pivotally mounted upon a horizontally disposed shaft 101 carried by a downwardly extending bracket 102. An arm 103 of the lever 100 extends oppositely from the pivotal axis and is fitted with a roller 104 which engages a cam groove 105 of a cylinder cam 106. The cam 106 is mounted on the lower shaft section 30 of the main drive shaft and thus as the shaft 30 rotates it will oscillate the lever 100 and act through the lever arm 99 to reciprocate the lower chuck spindle 76.

Disposed parallel to the shaft 85 which carries star wheel 87 and upon the opposite side of the axis 59 is a shaft 107. This shaft is formed with a disc-shaped head 108 which fits within a recess of a plate 109 carried on the lower end of a bushing 110 and directly secured to an enlarged bushing end plate 110'. The bushing end plate 110' and the plate 109 are formed with a slotted opening 113 through which a screw 114 may pass to engage a threaded opening in the hub member 53. Within the bushing 110 is the lower end of the shaft 49. The bushing may, therefore, rotate around the axis of the shaft 49, and since the axis of shaft 107 is eccentric to the axis of shaft 49 lateral adjustment of the shaft 107 may be brought about, after which the bushing can be clamped into place by the set screw 114. This will hold the shaft 107 in a desired position of adjustment with relation to the shaft 85 for a purpose to be hereinafter set forth.

The lower end of the shaft 107 is pinned to a casting 117. This casting is formed with a collar 118 adjacent its upper end and has a downwardly extending tubular extension 119 which is concentric with the central axis of the shaft 107. The lower portion of the tubular extension 119 is split and is formed with bolting flanges 120 to receive bolts 121. By this means the tubular extension may be clamped on to a shaft 122 which extends downwardly through a lower bearing plate 123 carried by the base portion 10. Thus the entire structure including the member 117 may be raised and lowered to be adjusted with relation to the seaming head and also may be adjusted laterally with relation to the longitudinal axis of the spindle 76 so that the machine may be easily adjusted to accommodate cans of different diameters and heights. In Fig. 4 the collar 118 is shown as carrying a spider structure 123'. This structure is formed with diametrically opposed can pockets 124 which partially encircle a can and cooperate with the star wheel 87 to hold the can in a circular shape as it is lifted upwardly and centered in the mouth piece 125. It is to be understood that the members 123 may be interchanged so that the pocket portions will be of an appropriate diameter to receive the particular can to be worked upon. The spider structure 123 is intermittently driven. This intermittent drive is created by a radial cam disc 126 which is formed with a plurality of radial camways 127. As shown in Figure 6 of the drawings there are five of these camways or grooves which may successively move into engagement with cam rollers 128 carried upon the oppositely extending arms of a cam lever 129. The cam lever 129 is mounted on a shaft 130 which is suitably housed in the base 10 of the structure. This shaft carries a gear 131 in mesh with a gear 132 which is mounted upon the lower portion 30 of the main drive shaft. In this way the cam shaft 130 is constantly driven and the shaft 122 is driven thereby through the intermittent driving mechanism comprising the lever 129, its rollers 128, and cam disc 126. Mounted upon the shaft 122 is a gear 133 which is in mesh with a gear 134 which in turn meshes with an idler gear 135. The idler gear 135 is in mesh with the gear 90 mounted upon the shaft 85. Through this gear train the shaft 85 will be intermittently driven in unison with the shaft 122. Attention is directed to the fact that Fig. 4 of the drawings shows a can spider 123' mounted upon the shaft 122, and in Fig. 3 of the drawings a star wheel 136 is shown mounted on the shaft 122 as a substitute for the spider 123'. It will be evident, however, that since these structures are fundamentally the same they will cooperate with the star wheel 87 in placing and holding the cans in shape as they are fed to the double seaming station, and that they will hold the cans in proper position for vertical movement into the seaming head and while the seaming operation takes place.

Mounted on the lower end of the portion 30 of the main drive shaft is a beveled gear 137 which is in mesh with a complementary gear 138. The gear 138 is carried on a jack shaft 139 mounted in bearings 140. These bearings are secured to a frame element 141 carried by the base 10. Mounted on the opposite end of the shaft 139 from that upon which the beveled pinion 138 is fastened is a sprocket wheel 142. This sprocket wheel receives an endless sprocket chain 81 which passes around idler sprockets 144 and 145 at op-

posite sides of the base 10 as more particularly disclosed in Figure 1 of the drawings. The sprocket chain is led through the side walls of the base 10, one end of it passing around a sprocket wheel 146 mounted upon a shaft 147 above the base. The sprocket chain is then led over a sprocket wheel 148 mounted upon a shaft 149 in a bed plate 150 of the base structure. The return end of the sprocket chain is then led around a sprocket wheel 151 and to the idler sprocket 144. The sprocket wheel 151 is mounted upon a shaft 152 and is held adjustably in a bracket 153 by which a suitable tension may be created on the chain. The transverse shaft 149 carries a sprocket 154. This sprocket receives a chain 155 which is led around a sprocket wheel 156. This wheel is carried upon the shaft 157 of the packer and is mounted on a frame extension 158. The packer comprises arms 159 extending radially from the shaft and carrying packing discs 160 at their outer ends. These discs are pivoted on the ends of the arms upon pivot pins 161 and are rigidly connected to links 162 having rollers 163 at their free ends. The rollers move along a cam track 164 as the shaft is driven and cause the packing discs 160 to feed it and follow within the mouth of cans 65 as the cans pass into the machine. This action causes the food contained within the can to be tamped down and compressed as the cans move toward the double seaming station. The shaft 147 carries a sprocket wheel 146. Flights 172 are mounted on the chain 81 and engage the cans as they are fed from the can timing and feeding mechanism.

35 The feeding and timing mechanism comprises an initial timing star wheel 173 and a feeding and accelerating star wheel 174. The timing star wheel 173 is formed with a plurality of pockets to receive the cans 65 as they are delivered from a can runway 175. Associated with the star wheel 173 is a disc 176 which rotates with the star wheel and on to which the cans are delivered. Along the path of the traveling cans as propelled by the star wheel 173 and its disc 176 is a guide member 177 which confines the can to an arcuate path of travel. The star wheel and the disc are mounted upon a shaft 178 driven in a manner to be hereinafter described. In a plane horizontally common to that of the upper surface of the disc 176 is a face 179 on the bed plate 150. Rotating above this face is the feeding and accelerating star wheel 174. This is mounted on a shaft 180 and is fitted with arms 181 which move into the path of travel of the cans as they rest on the disc 176 and advance the cans along an arcuate guide rail 182 to a position where they will be engaged by the flights 172 on the chain 81.

60 The can timing and feeding mechanism is driven from the shaft 149 which carries the feed sprocket 148 for the feed chain 81. This shaft carries a beveled pinion 183 which is in mesh with a beveled gear 184 mounted upon the shaft 180 upon which is also mounted the star wheel 174. Mounted upon the lower extending end of the shaft 180 is a gear wheel 185. This gear wheel is held for longitudinal adjustment upon the shaft 180 by a set screw 186 carried by its hub. Keyed on to the hub of the gear 185 is a second gear 187 of different diameter from the first gear so that suitable driving speed variation may be obtained. 65 A stub shaft 188 is carried in a bearing 189 of the bed plate 150 and carries a gear structure including a gear 190 and a gear 191 which are spaced from each other so that the gears 185 and 190 mesh or the gears 187 and 191 may mesh. Keyed

on to this gear structure is a gear 192. This gear is in mesh with a gear 193 carried upon a stub shaft 194 in a bearing 195 of the bed plate. The shaft 194 also carries a gear 196. The gears 193 and 196 are in mesh with gears 197 and 198 respectively which are carried upon the shaft 178 upon which the timing star wheel 173 is mounted.

The can cap feed mechanism generally indicated at 199 is of the type shown in Patent No. 1,935,443, entitled Can feed for double seaming machine, issued November 14, 1932. This structure is actuated by a lever 203 pivoted upon a bracket 204 and oscillated by an arm 205. The arm 205 is connected to a crank 206 which is carried upon the shaft 130 and rotates therewith. The cans as advanced by the feed plate 201 are carried on to guide rails 207 and 208. The path of travel of the feed plate 201 beneath the can stack 200 is parallel to the path of travel of the feed chain 81 and the cans carried thereby. The cap guide rails 207 and 208 have straight parallel portions receiving the can caps in their initial linear movement and concentric arcuate portions along which the can caps may travel to a position at right angles to that of the path of travel of the cans. While traveling in this position the star wheel 136 registers with the cap and moves the cap in an arcuate path of travel opposite to the arcuate path of travel prior to being engaged by the star wheel and feeds the cap over the can as particularly shown in Figure 3 of the drawings, so that the cap and the can will be in concentric registration when they reach the seaming station exactly in the vertical plane occupied by the longitudinal axes of shafts 85 and 107.

A suitable can cap marking mechanism is generally indicated at 209 in the drawing. This marking is connected through a driving link structure with a lever 210 mounted in the upper frame portion 25 of the machine and having a roller 211 which rides in the cam groove 37 of the cam drum 33.

The clutch structure 43 for controlling the driving of the machine is provided with a clutch collar 212 which receives slides 213 of a shifting yoke 214. This yoke is pivoted at 215 to a bracket 216. A lever arm 217 formed integral with the yoke 214 is fitted with an operating rod 218. This rod is connected with a lever 219 which is pivoted at 220 on the bracket 216. A control lever 221 shifts the lever 219 and thus operates the clutch. Attention is directed to the fact that a shoulder 222 is formed around the movable clutch member 43. This shoulder may be engaged by a lock element 223 to hold the clutch out of its driving position and to prevent it from being accidentally thrown into engagement with its complementary portion in the pulley 42.

In order that the cans of different size may be used in the machine the arcuate can guide rail 182 is fitted with slotted openings 224 to receive cap screws 225 by which the rail may be set for horizontal adjustment with relation to the bed plate 150. Complementary to the guide rail 182 is a guide rail 226 which is spaced from the guide rail 182 and is held by cap screws 227 which pass through slotted openings 228 in the guide rail 226. The cap screws in turn engage the face of the bed plate 150.

In operation of the present invention the cans 65 are fed into the chute 175 after having been filled with material to be sealed. The pockets of the timing star wheel 173 receive the cans and feed the cans around and along the arcuate rail

177. They are then engaged by the arms 181 of the star wheel 174 and are fed toward and along the arcuate portion of the guide rail 182. Attention is directed to the fact that the star wheel 5 173 and the star wheel 174 are spaced with relation to each other so as to cause the cans to move outwardly along the radial arms 181 and to thus be accelerated in lineal speed of travel so that when they move on to the feed chain 81 and are 10 engaged by the flights 172 they will be traveling at the lineal speed of travel of the chain. This insures that the cans will not be violently moved at any point in their travel, thus the contents of the can will not be spilled in transit from the runway 175 to the seaming station. As the filled can is moved with the chain 143 it is guided by the guide rails 182 and 226. The can then passes the packer unit where a packing disc 160 will move into the mouth of the can as the can travels and will insure that the contents of the can will be firmly pressed down into the can prior to receiving a cap. The caps 64 are fed from the cap stack 200 by the cap feed mechanism 199 and are moved along the cap guideways 207 and 208 until 15 they are traveling in a path of travel of the cans as moved by the chain 81. The caps will then be engaged by the arms of the star wheel 136 and will be rotated on an arcuate path of travel which is tangent to the path of travel of the central axis of the can as being moved along the chain 81. Thus the can and cap will be in direct superimposed central alignment when they reach the can double seaming station and are in coincident alignment with the chuck spindles 59 and 76. As 20 the cans move with the chain 81 they reach a position upon the lower chuck 79. This chuck is split to accommodate the chain and when the chuck is raised the can will be lifted upwardly and out of the path of travel of the flight 172 which has propelled it, and is then moved to a position where the can will lift the cap which is being supported by the guide rails and will carry the can and the cap upwardly into operative engagement with the upper chuck plate 63 so that 25 when the seaming head acts to operate and move the seaming rollers 72 around the lip of the can and the cap a double seaming operation will take place. It will be evident that the lower chuck intermittently reciprocates and that the driving operation of the seaming head is synchronized with that of the reciprocating lower chuck spindle 76. After the seaming operation has been completed and the lower chuck has moved to its 30 lowermost position the star wheel 136 will move the double seamed can and cap away from the seaming station so that another can and cap may be moved to the seaming station for a subsequent operation. It will be understood that the structure is intermittent in its action and that cans and caps will be rapidly fed to the machine, placed in assembled relation to each other and double-seamed, and that furthermore due to the manner in which the cans and caps are moved through the machine without excessive jar or vibration cans of large size and capacity may be 35 filled and seamed at high speed within the machine.

While I have shown the preferred form of my invention as now known to me, it will be understood that various changes might be made in the combination, construction, and arrangement of parts, by those skilled in the art, without departing from the spirit of the invention as claimed.

Having thus described my invention, what I claim and desire to secure by Letters Patent is:

In a can double seaming machine, a base structure, a lower can chuck associated therewith, means delivering cans to said chuck, a super structure disposed above the base structure, an upper chuck and seaming head carried by the super structure to act upon a can resting upon the lower chuck, a cap feed carried by the super structure, a star wheel carried by the super structure and delivering caps to the cans, driving means carried by the super structure for driving 10

the seaming head, driving means in the base structure for operating the lower chuck and the star wheel, an extensible driving member between the super structure and the base, an extensible driving member between the base and the star wheel, and means for vertically adjusting the position of the super structure with relation to the base.

HENRY L. GUENTHER.
